CLAIM

The ornamental design for a combination cork puller and foil cutter, as shown and described.

DESCRIPTION

FIG. 1 is a perspective view of a combination cork puller and foil cutter showing my new design;

FIG. 2 is a front view thereof, the back view being substantially the same;

FIG. 3 is a side view thereof, the opposite side view being substantially the same;

FIG. 4 is a top view thereof;

FIG. 5 is a bottom view thereof;

FIG. 6 is an enlarged, bottom perspective view thereof showing the foil cutters; and,

FIG. 7 is an enlarged side view of the corkscrew and handle portion shown separately for ease of illustration.
